United States Patent Office.

JOHN P. BUTZ AND ABNER McFARLAND, OF ENTERPRISE, INDIANA.

Letters Patent No. 77,956, dated May 19, 1868.

IMPROVEMENT IN GATES.

The Schedule referred to in these Letters Patent and making part of the same.

TO ALL WHOM IT MAY CONCERN:

Be it known that we, JOHN P. BUTZ and ABNER McFARLAND, of Enterprise, in the county of Switzerland, and in the State of Indiana, have invented certain new and useful Improvements in Gates; and do hereby declare that the following is a full, clear, and exact description thereof, reference being had to the accompanying drawings, and the letters of reference marked thereon, making a part of this specification.

Figure 1 represents this gate fastened, and at rest.

Figure 2 represents this gate elevated, and ready to swing open.

A and B represent the front and rear gate-posts respectively.

This gate is composed of a series of horizontal slats, $a a a a'$. The top one, reaching only part of the length of the gate, is pivoted at each end to the vertical pieces $b b'$, forming the front and rear cross-bars of the gate.

C represents a diagonal brace, running from front end of the bottom slat a to the end of lever D, to which it is pivoted.

E represents another diagonal brace, running from the junction of the lower slat, a , and the cross-bar b' , to near the end of and supporting the upper slat, a' , to which the lever D is also pivoted.

Attached to the brace C is the tongue or latch c, which fastens the gate near the top, at x.

g represents the ratchet-bar, which is designed to hold the lever D at any desired angle.

By bringing down the upper end of lever D toward the front gate-post, A, it raises the front end of the gate by means of its action on brace C, and withdraws the tongue or latch c from the groove at x, and also forms the balance of slat a' .

Having thus fully described our invention, what we claim as new, and desire to secure by Letters Patent, is—

1. The lever D, with the brace C, and the slats $a a'$, used as and for the purposes set forth.
2. The combination of the lever D with the brace C, and the latch c, and ratchet-bar g, as and for the purposes specified.

In testimony that we claim the foregoing, we have hereunto set our hands, this 20th day of November, 1867.

JOHN P. BUTZ,
ABNER McFARLAND.
